PORTABLE EXTENSION LIGHT SHIELD
WITH CLAMP

Thurman L. Day, Indianapolis, Ind.

Application July 19, 1950, Serial No. 174,608

3 Claims. (Cl. 240—54)

1

This invention relates to a portable extension light shield.

Light shields of a portable nature for use in garages and factories are old in the art. They are frequently called "trouble lamps." Some have hooks secured to them to enable them to be hung in any convenient location. Others have a different type of securing means. The difficulties encountered in connection with the use of such conventional shields are numerous. First, those which are hung by hooks or like means tend to turn from one side to the other as the extension cord is inevitably turned. Since most of such shields have a reflector to direct the path of light in the desired direction, it is obvious that as they swing from one side to the other, the light is trained for a while on the desired object and then alternately off of it. Second, whenever the conventional shields are placed flat on the floor or on a table they tend to roll out of position, thereby making them ineffective.

It is the primary object of the present invention to provide a shield which will eliminate the foregoing difficulties and disadvantages.

The main feature of the present invention resides in a simply constructed, easily operated clamp construction wherein one side of the shield itself serves as one of the clamping members.

It is a further object of the present invention to make possible the ready insertion and removal of the lamp bulb. Heretofore it has been the practice to provide a hinged top portion for the shield to make possible the insertion or removal of the bulb after the top has been swung back. This construction has been unsatisfactory since the top opening is generally not large enough to accommodate the hand.

An additional feature of the present invention lies in a hinged shield portion which enables one entire side of the shield to be opened and which thereby facilitates the insertion and removal of the lamp bulb.

The full nature of the invention will be understood from the accompanying drawings and the following description and claims:

In the drawings,

Fig. 1 is a side elevation view of the invention.

Fig. 2 is a top plan view thereof.

Fig. 3 is a side elevation view looking at the side thereof to which the clamping element is secured.

In the drawings, 10 shows the handle portion which receives and accommodates therewithin the extension cord (not shown) which cord is

suitably connected to a power source (not shown). The handle is provided with a suitable socket 11 for receiving therewithin the light bulb 12. Disposed about the bulb is the shield which comprises a substantially square configuration throughout most of its length with its lower portion inwardly tapered as shown at 13. More than one-half of the shield consists of wire elements 14 which are spot welded or similarly secured at the lower portion to the resilient clamping collar 15. This collar is of a size such that it may be clamped about the upper portion of the handle 10 to hold the wire cage section of the shield in the proper location. Extending across the upper portion of the wire cage section of the shield are wire elements 16 having their free ends looped or bowed at 17 to fit over the upper extremity of the wire element 18. The rest of the shield other than the wire cage section comprises a solid piece of metal or other suitable material 19, the inner portion of which serves as a reflector. The top of section 19 is apertured at 19a to accommodate the free ends of elements 16. This arrangement thus provides a hinge connection between the wire cage section and the fixed, solid section. It is consequently possible, whenever bulb insertion or removal is desired, to separate the clamping collar 15 from engagement with the upper portion of the handle. Then the wire cage section can be pivoted to a position where bulb insertion or removal is readily accomplished.

The clamping means include the lever 20 pivotally secured at 21 to the portion 19 of the shield. The upper extremity of this lever terminates at 35 a point which is level or coplanar with the upper end of the shield.

Mounted about the handle 10 immediately below the socket carried thereby is the split collar 22 having ears 23 formed therein. This collar has apertures formed through the ears so that the securing means 24, such as a bolt or screw may be received therethrough to hold the collar in clamping relation about the handle. On the opposite side of the collar from said ears, and interposed between the lower portion of the lever 20 and the collar is the spring 25, the innermost coil of which is suitably secured to the wall of the collar 22. This spring normally constrains the upper portion of the pivoted clamp or lever into abutting engagement with the metallic portion 19 of the shield by forcing outwardly the lever portion of the lever. When it is desired to clamp the shield in a position where it can best reflect light upon the work being accomplished, the

user presses inwardly on the bottom portion of the lever, thereby overcoming the constraint of the spring and separating the upper portion of the lever from abutting engagement with shield section 19. The pressure will, of course, be released once the shield is disposed in the desired position, whereupon the tension of the spring will once again force the upper portion of the lever into gripping engagement with the object to which the shield is connected. The object will, of course, be disposed between the inner face of the lever and the outer face of shield section 19.

It is also apparent because of the configuration of the shield that it will remain in position on a table or other flat surface, when placed there, and will not roll out of the desired position.

While the invention has been illustrated and described in detail in the drawings and foregoing description, the same is to be considered as illustrative and not restrictive in character.

The invention claimed is:

1. A combined shield and holder for a portable extension light having a handle, comprising a substantially square bulb-shielding cage carried by said handle, said cage including a solid reflector portion having three sides and a top and an independent and complementary wire portion defining three sides and a top, resilient clamping means carried by said wire portion and detachably connected to said handle, a hinge connection between the upper ends of said reflector and wire portions, and a clamping member cooperable with said cage to support it upon an object, said member comprising a single flat jaw pivotally mounted intermediate its ends to said cage, and resilient means normally constraining a portion of said member into abutting relation with said cage, said last mentioned means being interposed between said handle and a portion of said member remote from its clamping portion.

2. A combined shield and holder for a portable extension light having a handle, comprising a substantially square bulb-shielding cage carried by said handle, said cage having its lower extremity inwardly tapered and including a solid reflector portion and an independent and complementary wire portion, resilient clamping element carried by the lower extremity of said wire portion and detachably embracing said handle, a hinge connection between the upper ends of said reflector and wire portions, and a clamping member cooperable with said cage to support it

upon an object, said member comprising a jaw pivotally mounted on said cage adjacent the junction of said tapered lower extremity with the upper portion thereof, said member being normally disposed in substantially parallel relation to the longitudinal axis of said cage, and resilient means normally constraining the portion of said member above the pivotal mounting into abutting engagement with said cage, said last mentioned means being interposed between said handle and a portion of said member below said pivotal mounting.

3. A combined shield and holder for a portable extension light having a handle, comprising a bulb-shielding cage carried by said handle, said cage having its lower extremity inwardly tapered and including a solid light reflector portion having three sides and a top and an independent and complementary wire portion defining three sides and a top, a resilient clamping element of split ring type carried by the lower extremity of said wire portion and detachably connected to said handle, a hinge connection between the upper ends of said reflector and wire portions respectively, and a clamping member cooperable with said cage to support it upon an object, said member comprising an elongated straight flat jaw pivotally connected intermediate its ends to said cage adjacent its tapered extremity, the portion of said jaw disposed above the pivotal connection normally lying in abutting relation with the upper portion of said cage, the portion of said jaw disposed below said pivot normally lying in spaced relation to the tapered extremity of said cage and to said handle, and a coil spring interposed between said handle and a portion of said jaw disposed below said pivotal connection, said spring normally biasing the portion of said jaw above the pivotal connection into abutting relation with the upper portion of said cage.
